UNITED STATES PATENT OFFICE

LOUIS H. MESKER, OF SHAKER HEIGHTS, OHIO, ASSIGNOR TO THE CLEVELAND PLANER COMPANY, OF CLEVELAND, OHIO, A CORPORATION OF OHIO

HEAD CLAMP

Application filed June 11, 1928. Serial No. 284,517.

This invention relates to an improved head clamp for clamping the tool slide on a planing machine in one solid mass.

The main object of the invention is to provide an improved head clamp which effectively secures the several parts in adjusted position and which at the same time comprises comparatively few parts which may be adjusted with a minimum effort.

10 Another object of the invention is to provide a head clamp of the character described which rigidly secures the tool in place in such a manner that it will be possible to take any cut which the tool will stand and at the same time be especially accurate even for the heaviest cutting.

20 Still another object of my invention is to provide a head clamp which locks the slide in the most rigid manner without the necessity of any change of slide adjustment.

Further objects of the invention will appear as the description proceeds and by reference to the accompanying drawings in which Fig. 1 is a view in front elevation of my 25 improved head clamp applied to the head rail, Fig. 2 is a horizontal sectional view on the line 2—2 of Fig. 1; Fig. 3 is a vertical sectional view on the line 3—3 of Fig. 2 and Fig. 4 is a detail end view of one of the wedge 30 blocks.

The objects of the invention hereinbefore referred to are accomplished by the combinations and arrangement of parts to be hereinafter more fully described although it is to be understood that various changes may be made in the details of construction and shape of the several parts without departing from my invention and that I have illustrated only the preferred embodiment of my 40 invention.

Referring now to the accompanying drawings, the reference character 1 designates the head rail, which is preferably rectangular in shape and on which the rail head 2 is mounted. A pair of screws 3 and 4' extend longitudinally of the head rail and serve to move the head in either direction in a horizontal plane in a manner well known to those skilled in the art. Mounted on the rail head 50 2 is the tool slide 4 which carries the cutting

tool 5 which is secured in place in a manner also well known to those skilled in the art. The mechanism thus far described forms no part of the present invention except in so far as it cooperates with the mechanism 55 which will now be described.

The rail head 2 carries a member 7 shaped in section as shown most clearly in Fig. 2, the back portion of which is extended upwardly as shown in Fig. 1. The element 7 60 is generally referred to as the harp. Secured over the front of harp 7 is a movable block 8 generally termed the head slide which is shaped in section as shown in Fig. 2. The harp 7 is recessed at its central portion 65 as shown in Fig. 2 and the head slide is provided with a complementary recess, the purpose of which will hereinafter appear. For the purpose of identification the angular projections on the face of the harp are designated by the reference character 9. The head slide 8 is provided on its right side as seen in Fig. 2 with a longitudinally extending angular recess 12 which is slightly larger than the right hand projection 9 and extends the full length thereof. The head slide 8 is also provided with a somewhat annular opening or recess 13 which is adapted to receive an annular block or gib 14 which is preferably of brass and has one side tapered 80 as shown in Figs. 2 and 4. The block 14 is provided with a threaded opening 15 adapted to receive a threaded pin 16 therein which projects through an opening in the block 8 and is provided at its outer end with a handle 17. The outer end of the pin 16 is enlarged and is surrounded by a collar 18 against which the handle 17 bears. Attention is particularly called to the angularity 85 of the projections 9 and to the fact that the right hand projection does not fill the recess 12 in the head slide. Inserted in this space is a wedge or gib 19, the purpose of which will hereinafter appear.

The operation of the head clamp is as follows: The head is moved laterally to the desired position on the rail by means of the screws 4' and 3, the tool 5 having been first secured in the tool slide at the desired position. The head slide 8 may then be adjusted 100

vertically by means of the screw 6, the handle 17 having first been loosened to permit this movement. After the head slide has been set at the desired position, the handle 17 is turned 5 clockwise as seen in Figs. 1 and 2. This turning movement of the handle 17 tends to move the head slide 8 toward the harp 9 and due to the angularity of the projections 9 the head slide will also tend to move toward the 10 left as seen in Fig. 2 resulting in a wedging action between the right hand projection 9, the head slide 8 and gib 19 and also resulting in a wedging action between the left hand projection 9, the head slide 8 and the block 15 14. It will thus be seen that there is a wedging action in two directions at right angles to each other which serves to firmly and securely lock the parts in the adjusted position. It will also be clear that these parts are locked 20 by a very simple and efficient mechanism and that the position of the head slide may be changed without disturbing the adjustment of the tool in the tool slide.

It will now be clear that I have provided 25 a head clamp which will accomplish the objects of the invention as hereinbefore stated. Various changes may be made in the shape and arrangement of parts, as well as other details of construction, without departing 30 from the spirit of my invention and I wish my invention to be limited only in accordance with the scope of the appended claim.

Having thus described my invention, what I claim is:

35 In a device of the character described, a harp having a central groove for the reception of a tool adjusting screw, a pair of projections, one on each side of said groove adjacent the same, said projections extending longitudinally of said harp and having angular outer faces extending outwardly away from the body of said harp, said projections being spaced from the edges of said harp to provide harp body bearing surfaces, a head 40 slide cooperating with said harp and being provided with head slide projections adjacent the edges thereof, said projections having bearing faces adapted to cooperate with said harp body bearing surfaces, the inner 45 faces of said head slide projections interlocking with said angular outer faces, a gib between one of said angular outer faces and one of said inner faces, there being a single circular bore through one of said head slide 50 projections having its outer edge substantially at the edge of said projection, an annular block having one beveled side, said block being positioned in said bore and fitting snugly 55 therein, and means extending through said slide for pulling said block toward the slide to cause said bevel on said block to wedgingly grip the adjacent projection on said harp, the lengths of said projections being such 60 that bearing contact is attained between those

bearing surfaces which are adjacent the edges of the harp and slide.

In testimony whereof, I hereunto affix my signature.

LOUIS H. MESKER.
